UNITED STATES PATENT OFFICE.

FRANK G. KAMMERER, OF CHICAGO, ILLINOIS.

GLASS-RINSING DEVICE.

SPECIFICATION forming part of Letters Patent No. 737,247, dated August 25, 1903.

Application filed September 17, 1902. Serial No. 123,681. (No model.)

To all whom it may concern:

Be it known that I, FRANK G. KAMMERER, of Chicago, in the county of Cook and State of Illinois, have invented certain new and useful Improvements in Glass-Rinsing Devices; and I do hereby declare that the following is a full, clear, and exact description thereof, reference being had to the accompanying drawings, and to the letters of reference marked thereon, which form a part of this specification.

This invention relates to improvements in devices for rinsing tumblers and like articles, the same being more especially adapted for use in connection with liquid-dispensing apparatus, soda-fountains, and the like, while being capable of use for other purposes.

The invention consists in the matters hereinafter described, and pointed out in the appended claims.

In the accompanying drawings, illustrating my invention, Figure 1 is a view in central vertical section of an apparatus or device embodying my invention. Fig. 2 is a plan view thereof. Fig. 3 is a detail sectional view showing a modification of certain of the parts.

As shown in said drawings, A indicates a vertical water-delivery pipe, the upper end of which constitutes the discharge-nozzle of the rinsing device and which is connected at its lower end with a water-supply pipe B. Said delivery-pipe A is surrounded by annular walls C and D, which form an annular channel or recess E to receive the edge on the lower margin of a tumbler when placed in an inverted position over the pipe A, said annular chamber or space E being closed at its bottom by a bottom wall, herein shown as having the form of an outwardly-extending flange or extension D' of the inner wall D. The outer annular wall C is shown as supported from or upon the pipe A by means of a circular plate F, the same having a central aperture for the passage of said pipe A and said plate being secured to the lower part of the pipe. At its outer edge the said plate F is provided with a depending annular flange which fits within the annular wall C and is secured thereto by screws or otherwise. The outer margin of the plate F is shown as arranged in contact with the outer margin of the flange D', and these parts will preferably

be secured together, so that the plate F supports the lower part of the wall D concentrically with respect to the pipe A. The upper part of said inner wall D is preferably deflected inwardly or made of dome shape, so as to fit around the upper part of said pipe A, the said inner wall thereby serving to brace or hold from lateral movement the upper end of said pipe A. Holes d d for the drainage of water from the recess E are formed in the flange D' and the plate F. The annular walls C and D with the flange D' form the outer and inner walls of the annular receptacle E to receive the lower margin of a glass or tumbler placed in an inverted position over the delivery-pipe A, said outer and inner walls serving to aid in holding the glass or tumbler in place on or over the delivery-pipe and the receptacle serving to hold water to aid in the rinsing of the edge of the glass, as will hereinafter more fully appear.

Beneath the several parts described is located a drainage cup or receptacle G, adapted to receive water escaping from the upper part of the apparatus and conduct the same to a drainage-pipe H. Said drainage-pipe H is shown as connected centrally with the cup G at a point beneath the pipe A. The supply-pipe B is shown as connected with the pipe A by means of a fitting B', provided with a double bend, which brings its vertical part or stem b, which passes through the cup G, at one side of the pipe H. Said drainage-pipe is shown as affording the means for supporting or holding in place the cup G as well as the other parts of the apparatus. A tight joint is formed between the vertical part b of the fitting B' and the cup G by means of a collar I, which is located beneath the cup and shaped on its upper surface to correspond with the inclination or curvature of the bottom of the cup, the fitting B' being provided above the collar I with a flange b', between which and the collar I the metal of the cup G around the margins of the aperture therein is clamped by the action of a nut i, applied to the stem beneath the collar.

The lower margins of the outer wall C of the receptacle E are shown as extended downwardly past the plates F to the bottom of the cup G, small drainage-openings c being formed at the lower margin of the lower part of the

wall C, so as to permit water which may overflow from the recess E and which falls into the outer part of the cup G outside of the wall C to reach the inner part of said cup and 5 the drainage-pipe H.

Now referring to the devices shown for controlling the flow of water from the upright delivery-pipe A, devices are provided as follows: Said pipe A is provided with an interior 10 downwardly-facing valve-seat a, which is preferably and conveniently formed at the lower end of said pipe A or at the point where said pipe A joins the fitting B', but which may be located elsewhere in the pipe A, as 15 may be found convenient or desirable.

J indicates a valve disk or closure which fits the seat a and is attached to a valve-stem K, which reaches upwardly through the pipe A to the upper end thereof and has attached 20 to it an enlargement or head L, which moves freely in the upper end of the pipe A. The head L is slightly smaller in diameter than the interior of that part of the pipe A which surrounds it, so that a narrow annular outlet 25 for water is formed between the head and the upper end of the pipe. Between said head L and an upwardly-facing shoulder a' in the pipe A is located a coiled expansively-acting spring M, which by upward pressure on the 30 head L serves to normally hold the valve-disk J in contact with the seat a. Said head L is so arranged or placed at such elevation above the bottom of the recess E that a tumbler placed over the upper end of the pipe A with its lower 35 margin in said recess E will rest upon or be supported by the head L, with its lower edge above the bottom of the said recess E, and the spring M is made of such strength that it will hold the valve closed under the weight 40 of a tumbler so resting on the head L. As a result of this construction it is apparent that a tumbler placed upon the apparatus in the position shown in dotted lines will have no effect upon the valve J and will be held 45 or retained in the position shown with its weight resting on the head L. By pressing downwardly upon the tumbler, however, the spring M will be compressed and the valve J opened, so that a supply of water may be delivered 50 through the pipe A at any time for the purpose of rinsing the tumbler by merely pressing downward upon the tumbler as it rests upon the apparatus. The head L being made somewhat smaller in diameter than the 55 open upper end or nozzle of the delivery-pipe A water will be thrown in the form of an annular stream, jet, or spray upwardly from the pipe against the bottom of the tumbler and will spread or be deflected outwardly 60 thereby, so that it will descend along the inner surface of the tumbler, and thereby rinse the entire surface thereof. The openings e in the bottom of the annular recess E are made of such small size that the water will 65 run from the said recess more slowly than it is supplied thereto by the pipe A, so that when pressure is applied to the tumbler for

opening the valve the water will rise in said recess around the lower edge of the tumbler, and thereby rinse the outer as well as the 70 inner surface of the marginal part thereof. If the tumbler be held depressed so long that the water overflows from the recess E, the escaping water will be caught in the outer rim of the cup G and will find its way to the 75 drainage-pipe.

In order to prevent the controlling-valve being opened and water escaping from the delivery-pipe by downward pressure on the head L when there is no tumbler in place on the apparatus, I make said head of tapered or conical form and provide it at its upper end with a sharp point which serves to prevent sufficient pressure being brought thereon by the hand or finger to open the valve, 80 it being of course understood that the presence of such sharp point is not at all detrimental to the operation of the device when a tumbler is resting thereon.

Instead of supplying the fixture B with a 90 double bend, as shown in Fig. 1, the supply-pipe may be straight and arranged concentrically with respect to the drainage-opening of the cup G, this construction giving a more symmetrical form to these parts of the device. 95 Such a construction is illustrated in Fig. 3, in which a straight pipe-fitting B² is used, and the cup G is attached to a circular fitting N, made larger in diameter than the fitting B² and through which the latter passes. The 100 fitting N is shown as provided with holes n in its top through which the waste water enters the same from the cup G and as having a waste-pipe O leading from one side thereof, the bottom wall of said fitting being provided 105 with an opening for the passage of the lower end of the fitting B², which latter is screw-threaded and provided above the said bottom wall with a shoulder b² and below the same with a nut b³. 110

I claim as my invention—

1. A device for the purpose set forth comprising an upright delivery-pipe provided with an internal, downwardly-facing valve-seat, a valve-closure engaging said seat and 115 provided with a stem which rises through the said pipe, an enlarged head on the stem which slides in the upper end of the pipe and projects above the same, and a coiled, valve-actuating spring which surrounds the upper 120 part of the stem and bears at its upper end against the bottom surface of said head and at its lower end against an annular, upwardly-facing shoulder located within the pipe above the valve-seat. 125

2. A device for the purpose set forth comprising an upright delivery-pipe provided with an internal valve, means for actuating the valve comprising a downwardly-yielding head which projects above the top of the pipe, 130 an annular receptacle surrounding the delivery-pipe consisting of inner and outer, sheet-metal side walls arranged concentrically with said delivery-pipe, and a bottom wall connect-

ing said inner and outer walls, said annular receptacle being adapted to receive the lower edge of a tumbler placed over the upper end of the delivery-pipe and being provided with a drainage-opening, and a lower cup or receptacle arranged concentrically with the delivery-pipe below the bottom of said annular receptacle, and provided with a drainage-pipe, and a water-supply pipe which passes through the bottom of said lower cup or receptacle and is connected with the delivery-pipe.

3. A device for the purpose set forth comprising an upright delivery-pipe, an annular receptacle surrounding the delivery-pipe consisting of inner and outer sheet-metal side walls arranged concentrically with said delivery-pipe and a bottom wall connecting said inner and outer walls, said annular receptacle being provided with a drainage-opening in its bottom, a plate which is attached to the lower end of the delivery-pipe and to the bottom of said annular receptacle, and serves to support said receptacle concentrically with respect to the pipe, a lower cup or receptacle arranged concentrically below the annular receptacle, and a water-supply pipe which passes through the bottom of the said lower cup or

receptacle and is attached to the lower end of the delivery-pipe.

4. A device for the purpose set forth, comprising an upright delivery-pipe, an annular receptacle surrounding the delivery-pipe and consisting of inner and outer annular walls and a bottom wall connecting the same, said annular receptacle being provided with a drainage-opening, a lower cup or receptacle arranged concentrically with the delivery-pipe below the bottom of said annular receptacle, and provided with a drainage-pipe and a water-supply pipe which rises through the bottom of the said lower cup or receptacle and is attached to the lower end of the delivery-pipe; the outer side wall of said annular receptacle being extended downwardly below the bottom thereof, into contact with the lower cup or receptacle.

In testimony that I claim the foregoing as my invention I affix my signature, in presence of two witnesses, this 8th day of September,

A. D. 1902.

FRANK G. KAMMERER.
